RICHARD E. HAMMOND AND STANTON W. FORSMAN, OF COLORADO SPRINGS, COLORADO; MARY ELIZABETH HAMMOND RESIDUARY LEGATEE OF THE ESTATE OF SAID RICHARD E. HAMMOND, DECEASED.

STARTING DEVICE FOR EXPLOSIVE-ENGINES.

1,078,196.

Specification of Letters Patent.

Patented Nov. 11, 1913.

Application filed December 5, 1910. Serial No. 595,660.

To all whom it may concern:

Be it known that we, RICHARD E. HAMMOND and STANTON W. FORSMAN, citizens of the United States of America, residing at Colorado Springs, in the county of El Paso and State of Colorado, have invented certain new and useful Improvements in Starting Devices for Explosive-Engines, of which the following is a specification.

10 Our invention relates to starting devices for explosive engines and its principal object resides in the provision of a mechanism of simple construction which, when impelled by the expansive action of a motive fluid, will impart a rotatory movement to the shaft of the engine with which it is associated.

15 A further object of our invention resides in the provision of a governor of novel construction which, being controlled by variation in the density of the motive fluid stored in a reservoir which is connected with the starting mechanism, is adapted to automatically cause replenishment of said reservoir, by operative connection of a suitable compression pump with a rotatory part of the engine.

20 We attain these objects by the mechanism illustrated in the accompanying drawings in the various views of which like parts are similarly designated and in which—

25 Figure 1 represents a plan view of the chassis and engine of a motor vehicle, with the improved starting apparatus and the therewith associated reservoir and pipe connections in their operative position, Fig. 2, an enlarged section taken along the line 2—2, Fig. 1, Fig. 3, a section taken along the line 3—3, Fig. 2, drawn to an enlarged scale, Fig. 4, a horizontal section taken along the line 4—4, Fig. 2, Figs. 5 and 6, enlarged sectional views of the governor shown in Fig. 3 with the operative parts thereof in different positions, and Fig. 7, 30 an enlarged sectional view of the operating valve and adjacent parts of the pipe system by which the starting mechanism is connected with the source of motive fluid.

35 Referring to the drawings by numerals, 2 designates a casting which comprises a crank case 3, and two cylinders 4 and 5, which extend obliquely in opposite directions from

the upper portion thereof. The cylinder 5 is not essential in the operation of the apparatus, but is provided principally to render 55 the device symmetrical and attractive in appearance. By closing the lower end of this cylinder by means of a transverse partition, as is indicated in broken lines at 6 in Fig. 2, it may be employed as a reservoir for the 60 storage of motive fluid or liquids for various purposes or as a receptacle for tools and other articles. A piston 13 slidably fitted in the other cylinder, 4, is secured upon an extremity of a rod 8, which is supported in 65 the bore of a boss 9 formed internally at the junction of the divergent cylinders.

70 A rack 10 secured upon a longitudinally extending, flattened surface on the rod 8, meshes with a gear wheel 12, which is rotatably disposed within the crank case 3, in a manner hereinafter to be described, and the said rod has an axial recess for the reception of a coiled spring 7, the ends of which are attached respectively at the bottom of 75 the said recess and to a head 14 which closes the end of the cylinder 4. The gear 12 is loosely mounted upon a crank shaft 15 which is revolvably supported in bearings 16 formed integral with heads 17, which close 80 the opposite ends of the cylindrical crank case 3. A clutch 18, which may be of the ball-and-ratchet type or of any other construction suitable to the purpose, is applied to transmit the movement of the gear in one 85 direction, to the shaft 15, while it permits a movement of the latter in the same direction without effect upon the wheel 12. The shaft 15 is provided with a crank which, by means of pitmen 19, is connected with two 90 pistons 20, which have a reciprocating movement, respectively within cylinders 21 which are secured at opposite sides of the case 3, in axial alignment. The cylinders 21 with their respective pistons constitute pumps for 95 the compression of air which is drawn in through apertures 22 in the cylinder walls, and delivered past valves 23 in the ends of the cylinder, through openings 25 which, by means of pipes hereinafter to be described, 100 are connected with a reservoir in which the motive fluid by which the apparatus is actuated, is kept in store. A sleeve 26 longitudinally, movably mounted upon an extreme

portion of the shaft which extends outside the case 3, is by means of a feather 27, connected to rotate in unison therewith and it carries upon its outer extremity, a clutch member 28, the correlative 29 of which is secured upon the end of the engine shaft 30 with which the crank shaft 15 is axially alined. The clutch members 28 and 29 may be of any construction suitable to couple 10 the two shafts so that either of them may impart its rotatory motion to the other, and a spring 31 is applied between the slideable member 28 and a shoulder on the sleeve 26 for the purpose of permitting a longitudinal 15 movement of the latter even after the members of the clutch are in operative engagement.

A circumferential groove is formed in the sleeve 26 for the reception of a trunnioned collar 32 pivotally connected with a lever 33 which is fulcrumed at its upper end upon a bracket 34 extending laterally from the casting 2, and whose opposite extremity is pivotally connected with an operating rod 35 which may be moved longitudinally either by means of a foot lever 36 or by the action of a piston 37, which has a reciprocating movement in the cylindrical portion 38 of a governor which is attached 30 to a bracket 39 formed integral with the crank case 3.

The extremity of the crank shaft 15, opposite to that which carries the sleeve 26, has diametrically opposite studs 40 for connection of a hand crank to be applied in case it is desired to "crank" the engine in the usual manner, independent of the starting apparatus.

The governor above referred to consists 40 of a casing composed of two integral axially aligned cylinders 38 and 41, of dissimilar diameters, in which the before mentioned piston 37 and a smaller piston 42, are respectively, fitted for reciprocation. The 45 larger one, 37, of the two pistons is constructed at the end of a rod 43 which projects through aligned openings in the head 44 of the governor casing and a therewith contiguous bracket 39, and which is pivotally connected with an end of the operating rod 35, and the integral piston 37 and rod 43 have an axial recess into which the rod 45 of the smaller piston 42 slidably extends. A pin 46 which occupies transverse 55 openings in the rod 34, projects through a longitudinal slot in the rod 45 for the purpose of causing the two pistons connected with the said rods, to move in unison during a certain period in the action of the governor. 60 nor while it permits the larger one of the two pistons to move independently when it is employed to bring the clutch members 28 and 29 in engagement. The rod 43 is provided with an external screw thread for the 65 application of a nut 47 which by engage-

ment with the outer surface of the head 44, limits the rearward movement of the piston 37, and a screw stop 48 is adjustably connected with a head 49 at the opposite end of the governor casing, to limit the movement of the smaller piston in the same direction. The extent of the movement of the last mentioned piston in the opposite direction is determined by its engagement with one or more washers placed against the shoulder of the annular partition 50 which is formed at the junction of the two cylinders 38 and 41.

The differential cylinders have three ingress ports for motive fluid one of which, 70 51, is formed in the circumferential wall of the larger cylinder, in close proximity to the partition 50, while the two others, respectively designated in the drawings by the numerals 52 and 53, are in an enlargement of the wall of the smaller cylinder and branch from an opening 54 which connects with the conduit through which the motive fluid is supplied from the reservoir. The 75 position of the two ports 52 and 53 is such that when the piston 42 is in its rearmost position in engagement with the stop 48, as shown in Fig. 3, it is positioned between the said ports without closing one or the other, while when the piston is, at the end of its forward motion, in engagement with the washer placed against the partition 50, it 80 closes the port 52 while the other remains uncovered. A coiled spring 55 placed between the larger piston 37 and the head 44, serves to resiliently maintain the former in its normal position shown in Fig. 5 of the drawings, and a smaller spring 56 is placed within the recess, to engage the end of the piston rod 45 for the purpose of lessening 85 the concussive shock at the end of the forward movement of the piston 37, the entire extent of which is determined by the engagement of the nut 47 with the outer surface of the head 44. An exhaust port 57 in the circumferential wall of the larger cylinder 38 is disposed to discharge air from the space between the two pistons when the larger one has reached the end of its forward stroke as shown in Fig. 6.

Our improved starting mechanism has 90 been shown in Fig. 1 of the drawings, as applied to the chassis of a motor vehicle the radiator of which is designated by the numeral 58, the dash-board by the numeral 59, and the engine by the numeral 60. The casting 2 is rigidly secured in front of the radiator, with the crank shaft 15 in axial alinement with the shaft 30 of the engine, the foot lever 36 is placed within easy reach 95 of the operator, a reservoir 61 for the storage of compressed air is attached at a convenient point of the chassis, and an operating valve 62, by means of which the operator controls the flow of motive fluid from 100 105 110 115 120 125 130

the said reservoir, is disposed against the dash board 58. The valve 62 is attached at the end of a manifold 63, (as shown in Fig. 7), which is connected with the reservoir by means of a pipe 64, with the opening 54 in the governor by the use of a conduit 65, and with the two pump-cylinders 21 by means of pipes 66 and 67. The valve 62 is furthermore directly connected with an opening in the head 14 of the cylinder 4, by means of a conduit 68 and with the port 51 of the governor, by means of a branch pipe 69.

The flow through the various pipes may be obstructed by means of valves 70 and 71, and the end of the manifold opposite to that which carries the operating valve, is provided with a valve 72 and designed for the attachment of a hose connection in case it is desired to use the air stored in the reservoir 61, for inflating the tires of the vehicle or cleaning other parts of the same.

In the operation of our invention, a supply of air is kept in store in the reservoir, compressed to a density which varies between predetermined minimum and maximum degrees. The valves 70 and 71 are, under normal conditions, open, while the valves 72 at the end of the manifold and the operating valve 62 are closed. It will thus be seen that the ports 52 and 53, and the valve chambers of the pump cylinders are in continuous communication with the source of air supply, while the port 51 and the interior of the cylinder can be connected with the reservoir only by manipulation of the operating valve 62. If, while the engine 60 of the motor vehicle is in operation, the air pressure in the reservoir 61, diminishes until it reaches its determinate minimum degree of density, the governor automatically establishes the connection between the shafts 15 and 30, with the result that the engine 60 will operate the pumps until the air within the reservoir has reached the predetermined maximum degree of density when the connection of the two shafts is automatically broken by the action of the governor, the parts of which subsequently return to their normal position. It will thus be seen that while the engine is in operation, a supply of air in the reservoir, of a density which varies between the extreme degrees, is at all times, assured and if by leakage or other causes, the pressure of the air diminishes below the minimum while the engine is at rest, the latter may be started for the purpose of operating the pumps, in the usual manner by applying a crank to the end of the shaft 15 which carries the studs 40.

When the driver of a vehicle equipped with our improved starting apparatus desires to "crank" the engine for the purpose of inducing the proper introduction and ignition of gaseous fluid within its cylinders, he turns the operating valve 62 to the open

position, thereby bringing the interior of the cylinder 4 and the port 51 of the governor simultaneously in communication with the reservoir 62. The air acting upon the piston 37 causes a longitudinal movement of the operating rod 35 and the therewith connected lever 33 which moves the clutch member 28 in operative engagement with the member 29 on the engine shaft 30. The air introduced into the cylinder 4, at the same time impels the piston 7 whose movement is through the instrumentality of the rack and gear movement, converted into a rotary motion of the crank shaft, and the therewith coupled shaft of the engine 60. When by subsequent closing of the valve 62, the communication between the reservoir 61 and the cylinders 4 and 38 is discontinued, the springs 7 and 55 return the respective parts to their normal positions. The above described operation is performed independently of the means for automatically replenishing the reservoir, of which means the piston 37 and the spring 55 are parts, and which while greatly desirable by reason of their automatic action, are not positively essential in the operation of the starting mechanism proper, for should at any time, the pressure within the reservoir be reduced to the minimum, which can readily be ascertained by the use of a pressure gage placed in view of the driver, a pressure of the foot upon the lever 36 will at once connect the clutch members 28 and 29 and thus actuate the pumps which supply air to the reservoir until the required pressure has been obtained.

In describing the operation of the governor by the use of which the supply of air in the reservoir is automatically maintained at a degree of density above the minimum, attention is called to Figs. 5 and 6 of the drawings which, respectively show the parts in their normal position, and in the position they occupy when, by the action of the governor, the air in the reservoir has been compressed to its maximum degree of density and the connection between the engine shaft and the crank shaft 15 is about to be broken. When the pistons are in their normal position, as shown in Fig. 5, the smaller one, 42, which acts as a valve covers the port 52, while the port 53 admits air into the space of the cylinder 41, back of the said piston, to maintain it in engagement with the shoulder formed by the partition 50. The larger piston is at the same time near the end of its rearward stroke, being held against further rearward movement by the engagement of the pin 46 with the end of the slot in the piston rod 45, while the pressure of the air upon the smaller piston prevents the two pistons from moving in unison. In this connection, it should be understood that the tension of the spring 55

which resiliently opposes the forward movement of the piston 37, is an important factor in the operation of the governor. When the piston 37 is in its normal position and the spring 55 is partially relaxed, its expansive force is equal to the predetermined minimum pressure of air in the reservoir multiplied by the area of the smaller piston 42, while when the said spring is compressed to its highest degree, when the piston 37 has reached the end of its forward movement as shown in Fig. 6, its pressure is somewhat in excess of the determinate maximum pressure of air in the reservoir multiplied by the area of the larger piston. The ports 52 and 53 are, as hereinbefore explained, in continuous communication with the reservoir, and at no time in the operation does the piston 37 reach a position sufficiently forward to cover the port 51 whose communication with the reservoir is controlled by the valve 62. The reciprocating movement of the piston 37 during the operation of "cranking" the engine as hereinbefore described, does in no way affect the normal position of the smaller piston, for the reason that the extent of such movement never exceeds the length of the slot in the piston rod 45. It will thus be seen that, after the engine has been started as well as when it is at rest, the parts of the governor invariably occupy the position shown in Fig. 5, and that they will remain in this position as long as the pressure of the air in the reservoir is above the minimum and in excess of the pressure of the spring 55. When, however, by repeated usage or leakage, the density of the air in the reservoir is reduced to a degree below the minimum, the pressure of the spring will overbalance the air pressure upon the small piston 42 with the result that the larger piston is impelled forwardly to complete its forward movement the extent of which is determined by the engagement of the nut 47 with the bracket 39; and the piston 42 is moved against the stop 48 by the engagement of the pin 46 with the shoulder of the slot in its stem 45. The port 52 being thus opened admits air in between the two pistons and, inasmuch as the air pressure upon the face of the large piston is now in excess of the spring pressure, which it will be seen, is at this point in the operation less than the minimum air pressure multiplied by the area of the small piston, the piston 37 is moved forwardly against the pressure of the said spring, a distance sufficient to bring the clutch members 28 and 29 in operative engagement through the instrumentality of the operating rod 35 and the lever 33. The engine 60 now actuates the pumps which supply air to the reservoir through the pipes 66 and 67, and the continuously increasing density of the air within the reservoir, causes a corresponding for-

ward movement of the piston 37 against the pressure of the spring 56 until, just before it passes the exhaust opening 57, the pin 46 reaches the forward end of the slot in the rod 45 of the smaller piston, when the two pistons will move in unison until the larger one has passed the exhaust opening and the smaller one has synchronously been returned to its original position in engagement with the partition 50, in which position it is maintained by the air pressing upon its rearward surface. The moment the larger piston has passed the exhaust opening (see Fig. 6) the body of impellent air escapes into the atmosphere, and inasmuch as the smaller piston has closed the port 52, the larger piston is impelled rearwardly by the expansive action of the spring 55 until it has reached its normal position in which the pin 46 is in the rearward portion of the slot in the rod 45. The rearward movement of the piston 37, disconnected the shafts 15 and 30, and the entire system is now again in a condition to start the engine by adjustment of the valve 62, until the pressure of air in the reservoir is again reduced below the minimum when the above described operation is repeated.

It will be observed that when, during the operation of the governor, the clutch members have been brought in engagement, further forward motion of the piston 37, is absorbed by the spring 31 between the member 28 and the shoulder on the sleeve 26, and that the small spring 56 within the axial recess of the piston 37, will lessen the shock of concussion at the end of the rearward movement of the latter after it has passed the exhaust port 57.

While we have shown and described our starting apparatus in the best form now known to us, we wish it understood that various changes in the construction and arrangement of its parts may be availed of within the spirit of the invention.

What we claim and desire to secure by Letters-Patent is:—

1. A starting mechanism for explosive engines, comprising a rotary device adapted to be impelled by fluid pressure, correlative members constructed to join said device and a rotary part of the engine for coöperation, a contrivance for bringing said members in operative connection, a device for actuating said contrivance by fluid pressure, and auxiliary means to actuate the same by mechanical action.

2. A starting mechanism for explosive engines comprising a cylinder, a piston having a reciprocating movement therein, a rack connected with said piston, a rotary shaft, a gear loosely mounted thereon in operative engagement with said rack, a clutch on said shaft for the transmission of the rotary motion of the gear in one direction, correlative

means for joining said shaft and rotary part of the engine for coöperation, and means for admitting motive fluid to the said piston.

3. A starting mechanism for explosive engines comprising in combination, a reservoir for motive fluid, a rotary device adapted to be impelled by fluid pressure, correlative members for joining said device and a rotary part of the engine for coöperation, means for bringing said device in communication with said reservoir, means for bringing said members in operative connection, and a mechanism for supplying motive fluid to the reservoir and adapted to be actuated by a decrease in density of the fluid contained in said reservoir.

4. A starting mechanism for explosive engines comprising in combination, a reservoir for motive fluid, a rotary device adapted to be impelled by fluid pressure, a pump operatively associated with said device in communication with the reservoir, correlative members for joining said device and a rotary part of the engine for coöperation, a contrivance impelled by fluid pressure, for bringing said members in operative connection, means for admitting motive fluid of the reservoir to the said device and to the said contrivance, and means for actuating the latter automatically by a decrease in density of the fluid in the reservoir, whereby said members are brought in operative connection for actuation of the pump.

5. A starting mechanism for explosive engines comprising in combination, a reservoir for motive fluid, a rotary device adapted to be impelled by fluid pressure, a pump operatively associated with said device in communication with the reservoir, correlative members for joining said device and a rotary part of the engine for coöperation, a contrivance, impelled by fluid pressure, for bringing said members in operative connection, means for admitting motive fluid of the reservoir to the said device and to the said contrivance, means adapted to actuate the latter automatically by a decrease in density of the fluid in the reservoir whereby said members are brought in operative connection for actuation of the pump, and to automatically disengage said members by a subsequent increase in the density of the said fluid.

6. A starting mechanism for explosive engines comprising in combination, a reservoir for motive fluid, a rotary device adapted to be impelled by fluid pressure, correlative members for joining said device and a rotary part of the engine, for coöperation, a cylinder, a piston having a reciprocating movement therein, means actuated by the movement of said piston for bringing said members in operative connection, means for admitting motive fluid from the said reservoir to said device and to the said piston, a

pump operatively associated with the said device, in communication with the reservoir, and means for actuating said piston automatically by a decrease in density of the fluid within the reservoir.

7. A starting mechanism for explosive engines comprising in combination, a reservoir for motive fluid, a rotary device adapted to be impelled by fluid pressure, correlative members for joining said device and a rotary part of the engine, for coöperation, a cylinder, a piston having a reciprocating movement therein, means actuated by the movement of said piston for bringing said members in operative connection, means for admitting motive fluid from the said reservoir to said device and to the said piston, a pump operatively associated with said device, in communication with the reservoir, means adapted to actuate said piston automatically by a decrease in density of the fluid within the reservoir, and to automatically return it to its original position by a subsequent increase in density of the said fluid.

8. A starting mechanism for explosive engines comprising in combination, a reservoir for motive fluid, a rotary device adapted to be impelled by fluid pressure, correlative members for joining said device and a rotary part of the engine, for coöperation, a cylinder, a piston having a reciprocating movement therein, means actuated by the movement of said piston for bringing said members in operative connection, means for admitting motive fluid from the said reservoir to said device and to the said piston, a pump operatively associated with said device, in communication with the reservoir, an auxiliary conduit for admitting motive fluid from said reservoir, to said piston, a valve under fluid pressure, normally closing said conduit, and means adapted to move the valve so as to open said conduit, when the said pressure is decreased below a predetermined degree.

9. A starting mechanism for explosive engines comprising in combination, a reservoir for motive fluid, a rotary device adapted to be impelled by fluid pressure, correlative members for joining said device and a rotary part of the engine, for coöperation, a cylinder, a piston having a reciprocating movement therein, means actuated by the movement of said piston for bringing said members in operative connection, means for admitting motive fluid from the said reservoir to said device and to the said piston, a pump operatively associated with said device, in communication with the reservoir, an auxiliary conduit for admitting motive fluid from said reservoir to said piston, a valve under fluid pressure normally closing said conduit, means to effect a movement of said valve in unison with said piston, and a

spring adapted to maintain the latter in its normal position and to move the valve so as to open said conduit, when the said pressure is decreased below a predetermined degree.

10. A starting mechanism for explosive engines comprising a rotary shaft, a device for imparting a rotary movement to said shaft by fluid pressure, correlative members for joining said shaft and a rotary part of the engine for coöperation, means for bringing said members in operative connection, a reservoir for motive fluid, means for admitting fluid from said reservoir to said

device, a pump in communication with said reservoir and in operative connection with said shaft, and means for establishing a driving connection between said device and the said shaft, adapted to allow the latter to move independently of said device for operating said pump.

In testimony whereof we affix our signatures in presence of two witnesses.
